FIREBOX FOR A SELF-SUPPORTED FIREPLACE

Gerald Leroy Jonas, 689 Kansas St., San Francisco, Calif.

Filed July 29, 1963, Ser. No. 76,030

Term of patent 14 years

(Cl. D81—7)

FIG. 1

FIG. 4

FIG. 3

FIG. 1 is a perspective view of a firebox for a self-supported fireplace showing my new design,

FIG. 2 is a front view thereof,

FIG. 3 is a side view, and

FIG. 4 is a top plan view thereof.

The dominant features of my design reside in the portions shown in full lines.

I claim:

The ornamental design for a firebox for a self-supported fireplace, as shown and described.
